HANDBAG HANDLE

Richard Koret, New York, N.Y., assignor to Koret, Inc.,
New York, N.Y., a corporation of New York

Filed Dec. 30, 1964, Ser. No. 83,218

Term of patent 3½ years

(Cl. D87—2)

FIG. 1

FIG. 3

FIG. 1 is a side elevational view of a handbag handle showing my new design;

FIG. 2 is an end elevational view thereof; and

FIG. 3 is an enlarged cross-sectional view thereof taken on line 3—3 of FIG. 1.

I claim:

The ornamental design for a handbag handle, substantially as shown.
